UNITED STATES PATENT OFFICE.

WILLIAM F. MAHONY, OF WASHINGTON, DISTRICT OF COLUMBIA.

BOTTLE-STOPPER.

No. 812,058.

Specification of Letters Patent.

Patented Feb. 6, 1906.

Application filed May 1, 1905. Serial No. 258,294.

To all whom it may concern:

Be it known that I, WILLIAM F. MAHONY, a citizen of the United States, residing at Washington, in the District of Columbia, 5 have invented new and useful Improvements in Bottle-Stoppers, of which the following is a specification.

The present invention relates to disk stoppers for milk-bottles and like receptacles, 10 and has for its object to provide a stopper which, while forming a perfect closure for the bottle or jar, is of such construction that it may be quickly and readily removed from the bottle without the use of a tool or device 15 for unseating it and without danger of spilling or splattering the contents of the bottle during removal of the stopper.

In the drawings herewith I have illustrated one embodiment of my invention, and 20 in said drawings Figure 1 is a sectional view of the top or neck of a milk bottle or jar with the sealing-disk therein, the manner of unseating the disk being indicated by dotted lines. Fig. 2 is a plan view of the sealing-disk. Fig. 3 is a detail view, enlarged, of the tab and body portion to show the scoring at the point of juncture.

Referring to the drawings by numerals, 2 indicates the body of the disk, which is of ordinary construction and which may be made of any suitable material, preferably a strong cardboard. Projecting from one side of the disk 2 is a tab 3, preferably formed integral with the disk 2, said tab having an aperture 35 4 formed therein and so united to the disk as to form a substantially U-shaped tab projecting from the circumferential edge of the stopper.

The tab 3 and disk 2 are separated by 40 means of a scoring 5, which is in line with or a continuation of the circumferential edge of the disk 2, so that the tab 3 may be readily folded up at right angles to the body portion or disk 2 of the stopper when the said disk is 45 forced into the bottle-neck, as will be clear from Fig. 1, and this scoring 5 is by preference formed on the upper surface of the stopper, so that the tab 3 when bent up to right-angle position will not break off at the scoring-line, 50 and, furthermore, the under side of the stopper will present an unbroken surface or skin, so that there will be no point at which the liquid contents of the bottle can attack and soften the line of juncture between the disk 2

and tab 3 of the stopper, which would of course result in weakening the line of attachment of the tab 3 to the disk 2.

Preferably the aperture 4 is struck out of the tab along the line of juncture of the tab 3 and the disk 2, so that its inner margin is a continuation of and coincides with the circumferential edge of the disk 2, and in its completed form the stopper is a substantially U-shaped tab projecting from its edge. The bending up of the tab 3, therefore, may be readily accomplished, and there will be no break in the continuity of the circumferential edge of the disk 2 which can interfere with complete and accurate seating of the disk within the bottle-neck and perfect sealing of the bottle.

In forming the disk it will be observed that no abrupt angles are made at the points of juncture of the tab 3 and the disk 2, and, furthermore, the marginal edges of the aperture 75 4 are all struck on curved lines. This feature I find to be a valuable one in that the tendency of the tab to tear from the disk when subjected to pulling strain is much less than is the case where the tab and disk meet on sharp angles, and the marginal edges of the aperture 4 present angular corners, for obviously an angular corner or point of juncture between the tab and disk would present a spot at which the pulling strain would concentrate and tearing and separation of the parts naturally take place.

In practice the disk is removed from the bottle by inserting the thumb or finger nail in the aperture 4 in the manner shown in Fig. 1, with the knuckle of the thumb or finger resting upon the disk 2, as shown in said figure. In this position the thumb or finger acts as a lever, so that the edge of the disk carrying the tab can be readily pried out of its seat with slight exertion, as clearly shown in Fig. 1, and without danger of tearing the tab from the disk.

I am aware that it has been proposed to provide stoppers of the same general character as the one described above with pull-tabs by means of which they may be removed from their seats; but so far as I am aware a tab having an aperture formed therein by means of which it may be pried out of its seat by simply inserting the thumb or finger nail in the tab-aperture is novel. Furthermore, in the pull-tab stoppers now in use

and known to me the tabs have been joined to the body portion of the stopper along their entire width, so that when crowded into the seat in the bottle-neck an incomplete sealing 5 of the bottle results, due to the break in the circumferential edge of the stopper portion proper. In the present construction, however, the legs of the U-shaped tab cause no appreciable break in the stopper edge, so that 10 complete sealing is secured.

Having described my invention, I claim—

1. A bottle-stopper comprising a body portion, and a pull-tab projecting from the circumferential edge thereof, said tab having 15 an aperture formed therein to receive the thumb or finger nail.

2. A bottle-stopper comprising a body portion, and a projecting pull-tab formed integral with said body portion and having an 20 aperture therein to receive the thumb or finger nail.

3. A bottle-stopper comprising a body portion, and a pull-tab projecting from the circumferential edge thereof and having an aperture 25 formed therein, the inner margin of

said tab-aperture coinciding with the circumferential edge of said stopper.

4. A bottle-stopper comprising a body portion and a substantially U-shaped tab projecting from the circumferential edge thereof. 30

5. A bottle-stopper comprising a body portion, and a substantially U-shaped tab formed integral with said body portion and projecting from the circumferential edge thereof

35 6. A bottle-stopper comprising a body portion, an integral pull-tab projecting from the circumferential edge of said body portion and having an aperture therein, the marginal edges of the stopper and tab-aperture being formed on curved lines and without abrupt angles, whereby the tendency of the parts to tear is eliminated or reduced.

In testimony whereof I have hereunto set my hand in presence of two subscribing witnesses.

WILLIAM F. MAHONY
